(57) CLAIM

The ornamental design for a connector for flexible circuit boards, as shown and described.

DESCRIPTION

FIG. 1 is a top plan view;

FIG. 2 is a front elevation;

FIG. 3 is a bottom plan view;

FIG. 4 is a rear elevation; and

FIG. 5 is a right-side elevation;

FIG. 6 is a first auxiliary figure of the connector shown in use; and,

FIG. 7 is a second auxiliary figure of the connector shown in use, in which the subject article having a row of terminals is secured to a side edge of a flexible circuit board.

The broken lines showing the flexible circuit board in FIGS. 6 and 7 are included for the purpose of illustrating environmental structure only and form no part of the claimed design.

A left-side elevation appearing symmetrical with the right-side elevation is excluded from the drawings.

The connector for electrically connecting a flexible circuit board to wire ends not shown does have a tiltable pressing cover.
